UNITED STATES PATENT OFFICE.

CARL S. WEYANDT, OF PITTSBURGH, PENNSYLVANIA, ASSIGNOR TO CENTRAL ELECTRIC TOOL COMPANY, OF PITTSBURGH, PENNSYLVANIA, A CORPORATION OF PENNSYLVANIA.

RECIPROCATING MOTOR SYSTEM.

Application filed July 26, 1922. Serial No. 577,719.

My invention relates to reciprocating motor systems, and particularly to the operation of reciprocating motors, including those utilized for striking blows to tools, such as drills, riveters and the like.

In accordance with my invention, there are selected, by asymmetrical electrical conduction, that is, by electric valve action, from a source of alternating current a plurality of series of uni-directional current impulses, and the impulses of the different series are utilized to produce magnetic fluxes, or in effect a reciprocating magnetic flux, for reciprocating a magnetizable member, such as a reciprocating core or vibratory armature.

For this purpose there may be utilized a plurality of magnetic field-producing windings traversed respectively by the impulses of the different series transmitted through asymmetrical electrical conductors or electric valves connected respectively in the circuits of the windings and so related to the source of alternating current that the periods of conductivity of the several valves or asymmetrical conductors occur dissimultaneously, preferably alternately, whereby the magnetizable member is actuated first by the flux produced by one winding and thereafter in opposite direction by flux produced by another of the windings.

My invention resides in a system of the character hereinafter described and claimed.

For an understanding of my invention, reference is to be had to the accompanying drawings, in which:

Fig. 1 is a diagrammatic view showing my method in which two electron tubes are employed; Fig. 2, a longitudinal section of an electric hammer which is operated by my invention; Fig. 3, a cross-section of Fig. 2 on the line III—III; and Fig. 4, a curve showing the wave forms impressed on the electromagnetic means which operate the reciprocating elements of an electromagnetic hammer, riveter, drill, or similar tool. Fig. 5 is a diagrammatic view showing my invention applied to a vibratory motor.

Referring first to Fig. 1, 1 and 2 designate alternating current supply lines, across which the primary winding 3 of the transformer 4 is connected. The transformer has two secondary windings 5 and 6, the former being in series with the filament 7

of the electron tube 8, and the latter being 55 in series with the filament 9 of the electron tube 10. Current from the line 1 is supplied to the tube 8 by the wire 11, and from the line 2 to the tube 10 by the wire 12. The anodes or plates 13 and 14 of the tubes are 60 connected by the wires 15 and 16 to the contacts 17 and 18 of the switch S. The movable contacts 19 and 20 of the switch are insulated from each other and connected respectively to one terminal of the windings 65 21 and 22, the other terminals being connected by the wires 23 and 24 to the supply lines 2 and 1. The contacts 19 and 20 are carried by the armature 25, retracted by spring 25^a, which is provided with the operating winding 26, connected to the wire 24 and the fixed contact 27 of the push-button or trigger switch 28, the other fixed contact 29 of the switch being connected to the wire 23. 30 is the movable contact carried 70 by the switch.

31 is a core member caused to reciprocate by flux generated by electric current flowing alternately in the windings 21 and 22.

The operation of the invention will be better understood after the structure of the electric hammer which I prefer to employ and have shown in Figs. 2 and 3, has been described. Referring to these figures, 32 is a non-magnetic cylinder or barrel in which the 80 magnetic core, armature, or striking element 31 is reciprocable. The barrel has at one end the external threads 34 and at the other end the internal threads 35, and surrounded by two electromagnets 36 and 37 which have 85 the respective windings 21 and 22 and whose magnetic circuits are separated by the fibre washer 38. The magnets have their magnetic circuits composed partly of the steel casing 39 and partly of L-shaped steel field 90 members 40 arranged radially around the barrel. Each member 40 has a radial arm 41 lying against an end of a winding and an arm 42 lying parallel with the barrel between the latter and a winding. Each magnet has two annular series of field members with the free ends of the arms 42 of one series facing or opposite the corresponding ends of the other series, these ends being beveled and having lugs or extensions 43 in 95 slots in the barrel 32. The outer ends of the arms 41 engage the casing 39.

44 is a cap screwing on the threads 34 and

having the flange 45 which bears against a fibre washer 46 imbedded in the inner wall 47 of the opening 48 in the handle 49. A short fibre ring 50 lies between the cap and the handle and abuts against the washer 46. A fibre washer 51 abuts against the inner end of the handle and the ring 50 surrounding the cap, and bears against the inner end of the casing 39. A fibre washer 52 lies between the cap and the casing, and also between the washer 51 and the arms 41 nearest the handle.

The handle end of the barrel contains the reciprocable hollow core-stop 53 having its outer end closed and having the flange 54 working in the enlarged portion 55 of the barrel and limited in its inner movements by the shoulder 56 and in its outer movements by the coiled spring 57 between the closed ends of the cap and core-stop. 58 is a set-screw threaded in the handle and engaging the cap 44 to prevent the accidental loosening of the cap.

59 is a non-magnetic nose piece or cap which engages the outer end of the casing 39, surrounds the outer end of the barrel, and has a flange 60 abutting against the said end of the barrel. A steel tool bushing 61 extends through the cap 59, screws into the threads 35, and has the flange 62 which engages the washer 63 on the end of the cap 59.

64 is a tool, such as a riveting tool, or a drill, having the shank 65 slidable in the tool bushing 61, the tool having a shoulder 66 adapted to engage the bushing when the tool is in its innermost position, as shown in Fig. 2. When in this position the end of the shank projects beyond the inner end of the bushing and lies about opposite the outer circle of lugs 43, preferably about as shown in Fig. 2. Of course, good results may be had if the end of the tool is not placed precisely as shown.

The parts being assembled as described and shown, they may be very closely drawn together by turning the cap 44 and securely locked by the set-screw 58.

The core 31 is provided with longitudinal slots 67 to prevent eddy currents.

The operation of the apparatus shown in Figs. 1, 2, and 3 is as follows: Current from the secondaries 5 and 6 makes the filaments 7 and 9 glow. When the trigger 28 is operated to cause the contact 30 to close the contacts 27 and 29, current flows from one line, as 2, through the wire 23, the winding 26 and the wire 24 to the other line, as 1. This current causes the switch S to close, which connects the winding 21 in series with the contacts 19 and 17, the plate 13, the filament 7 and the wire 11, the winding 21 being thus connected across the lines 1 and 2. Also when the switch S closes, the winding 22 is connected in series with the contacts 20 and 18, the wire 16, the plate 14, the filament

9 and the wire 12, the winding 22 being thus connected across the lines 1 and 2, but in the reverse order from the connection of the winding 21 to the lines.

Electron tubes of the general type shown 70 are well known as rectifiers of alternating current. They permit the passage of what is traditionally called positive current and prevent the passage of negative current. They permit alternations of one sign to pass 75 and suppress alternations of the opposite sign.

Assuming the core 31 to be in the position shown in the drawings and that a positive alternation is supplied to the line 1 and a negative to the line 2, current from the line 1 will flow through the electron tube 10 and the winding 22, but the current from the line 2 will be suppressed by the tube 8, thereby leaving the winding 21 unenergized. Flux 85 generated by the winding 22 pulls the core 31 to the left and causes it to strike the stem 65 of the tool 64. At or about the time the core reaches the limit of its first stroke, which is at about the end of the first half 90 cycle of the alternating current, a positive alternation is impressed on the line 2 and a negative on the line 1. Then positive current flows through the winding 21, but negative current is blocked by the tube 10, 95 thereby causing the winding 22 to be unenergized. Current in the winding 21 generates flux which pulls the core to the right and into contact with the yielding core-stop 53. At about this time, which is at the end of 100 the second half cycle, a positive alternation is impressed on the line 1 and a negative on the line 2, whereupon a second cycle of core movements begins, the cycles continuing as long as the switch S remains closed. The core 31 reciprocates in synchronism with 105 the consecutive alternations of the current impressed on the lines 1 and 2. The core 31 moves in one direction in substantial synchronism with one alternation of a cycle of 110 the impressed current, and in the opposite direction in synchronism with the second alternation of that cycle, and so repeatedly.

I do not restrict my invention to any definite number of electron tubes or definite 115 type of electron tubes, but have found the tungar to be satisfactory. I do not limit this invention to the use of electron tubes. I have herein adopted the old conception of positive current flowing contrary to the direction of flow of electrons passing from the lighted filament to the plate.

Fig. 4 shows the consecutive wave-forms of positive current impressed on the windings 21 and 22 by the apparatus of Fig. 1. 125 In this figure the generally sinusoidal curve V represents the electro-motive-force impressed by the source of alternating current connected to the supply conductors 1 and 2. Due to the asymmetric conductivity of the 130

valve 8, Fig. 1, and the inductance of its circuit, there traverse the winding 21 the successive current impulses indicated at 21 in Fig. 4. Each of these impulses begins at 5 the beginning of a cycle of the impressed electro-motive-force V and persists for materially more than a half cycle, as indicated. Due to the asymmetric conductivity of the valve 10 and the inductance of its circuit, 10 there traverse the winding 22 the successive current impulses indicated at 22, Fig. 4. These impulses are similarly of greater duration than a half cycle of the impressed electro-motive-force, and they begin 180 electrical 15 degrees later than the impulses 21, that is, they start at the beginning of the second half of each cycle of the impressed electro-motive-force V. Accordingly, the impulses 21 of one series to some extent overlap, in time, the impulses 22 of the other series. However, the impulses 21 traversing the winding 21 cause successive return movements of the core 31 against the back stop 53, and the impulses 22 cause successive 20 forward movements toward the left, against the shank 65 of the tool 64. The frequency of movement or reciprocation of the magnetizable member 31 corresponds with or is dependent upon the frequency of the alternating current source.

In Fig. 5, I show the two windings 21* and 22* arranged on the fields 40* at opposite sides of the vibratory armature 31*, these features corresponding in the parts 21, 35 22, and 31, respectively, on Figs. 1 and 2.

The construction and design of the electric hammer that is illustrated in this application is claimed in my co-pending application relating to electric tools, Serial 40 No. 577,720, filed July 26, 1922.

This application is a continuation in part of my copending case Serial No. 541,517, filed March 6, 1922.

I claim—

45 1. In a system for reciprocating electric motors, a reciprocable magnetic element, a pair of windings inductively related to the element so that when one is energized alone it will cause the element to move in one direction and when the other is energized alone it will cause the element to move in the opposite direction, alternating current supply lines, each containing one of the said windings and an electron rectifying means in 50 each circuit.

2. In a system for reciprocating electric motors, a reciprocable magnetic element, a pair of windings inductively related to the element so that when one is energized alone it will cause the element to move in one direction and when the other is energized alone it will cause the element to move in the opposite direction, alternating current supply lines, two circuits reversely bridged 60 across the supply lines, each containing one

of the said windings, and a two-electrode electron rectifying means in each circuit.

3. In a system for reciprocating electric motors, a reciprocating tool, a winding for operating the same in one direction, an electron rectifier in circuit with the winding, a source of alternating current connected to the winding and the rectifier and supplying operating current to the said coil, and electron rectifying means for operating the tool 75 in the opposite direction.

4. In a system for reciprocating electric motors, an electromagnet, an armature therefor, electronic rectifying means for transmitting current from a source of alternating current to the winding of the electromagnet to move its armature in one direction, a second electromagnet arranged upon energization to move the armature in the opposite direction, and a second electronic rectifying means for transmitting to the winding of the second electromagnet the remainder of the alternating current from said source.

5. The combination with an electrically-operated tool embodying a reciprocating plunger and plural operating windings for actuating said plunger in opposite directions, respectively, of a source of alternating current and means providing two current paths of asymmetrical conductivity connecting said windings to said circuit, respectively, one of said paths being responsive to current waves of one polarity and the other of said paths being responsive to current waves of the other polarity.

6. In a system for electric reciprocating motors, a reciprocating member, a pair of windings which respectively move said member in opposite directions, a source of alternating current for supplying power-producing current to said windings, and thermionic means through which said source delivers to said windings, respectively, two series of separate unidirectional impulses 105 of current of different signs, each series of impulses corresponding with the alternate half-waves of current of one sign of said source, whereby said member reciprocates in synchronism with the current waves of 110 said source.

7. The method of operating a reciprocating motor provided with a movable magnetizable member, which comprises selecting from a source of alternating current by 120 asymmetrical electric conduction two series of current impulses, the impulses of one series alternating with those of the other series, producing magnetic fields by said impulses, and actuating said magnetizable member in opposite directions by said fields.

8. The method of operating a reciprocating motor provided with a movable magnetizable member, which comprises selecting from a source of alternating current by 130

- asymmetrical electrical conduction two series of current impulses, the impulses of one series alternating with and overlapping those of the other series, producing by the 5 impulses of the different series reciprocating magnetic flux, and actuating said magnetizable member in opposite directions by said flux.
9. A reciprocating motor system comprising a reciprocating magnetizable member, a plurality of windings for producing magnetic fields displaced from each other along the path of movement of said magnetizable member, for actuating said member in opposite directions, a source of alternating current, and an asymmetrical electrical conductor in circuit with each of said windings and said source for causing passage of substantially uni-directional current impulses, said 15 asymmetrical electrical conductors being so related to said source that the impulses traversing one of said windings alternate with those traversing another of said windings.
10. A reciprocating motor system comprising a reciprocating magnetizable member, a plurality of windings, a source of alternating current, and an asymmetrical electrical conductor in circuit with each of said 20 windings and said source for causing passage of substantially uni-directional current impulses, said asymmetrical electrical conductors being so related to said source that the impulses traversing said windings alternate with each other to produce reciprocating 25 magnetic flux for actuating said magnetizable member in opposite directions.
11. A reciprocating motor system comprising a reciprocating magnetizable member, a plurality of magnetic field members 40 having air gaps with respect to which said magnetizable member is movable, a plurality of windings for energizing said magnetic field members, a source of alternating current, an asymmetrical electrical conductor 45 in circuit with each of said windings and said source for causing passage of substantially preponderantly uni-directional current impulses, said asymmetrical electrical conductors being so related to said source 50 that the impulses traversing said windings move said magnetizable member in opposite directions past the positions of minimum length of said air gaps.
12. A reciprocating motor system comprising a reciprocating magnetizable member, a plurality of windings, a source of alternating current, and an asymmetrical electrical conductor in circuit with each of said 55 windings and said source for causing passage of substantially uni-directional current impulses, said asymmetrical electrical conductors being so related to said source and to said windings that the impulses traversing said windings alternate with and overlap each other to actuate said magnetizable member in opposite directions.

In testimony whereof I hereunto affix my signature this 22nd day of July, 1922.

CARL S. WEYANDT.
